UNITED STATES PATENT OFFICE.

EDWARD B. CASTELLO, OF CHICAGO, ILLINOIS.

VEGETABLE-PARER.

1,071,603.

Specification of Letters Patent. Patented Aug. 26, 1913.

Application filed March 17, 1913. Serial No. 754,665.

To all whom it may concern:

Be it known that I, EDWARD B. CASTELLO, a citizen of the United States of America, and a resident of Chicago, county of Cook, 5 and State of Illinois, have invented certain new and useful Improvements in Vegetable-Parsers, of which the following is a specification.

My invention relates to vegetable parers 10 and cutters, and has for its object improvements in devices of that character.

In the accompanying drawings Figure 1 is a plan; Fig. 2 is a bottom view; Fig. 3 is a longitudinal section; and Fig. 4 is a 15 section on line 4—4 of Fig. 2.

The present device is made complete from only two pieces of sheet metal formed up and held together by a spring relationship of the two to each other. A part of one of 20 these pieces is bent to form a tubular handle A having a coring point B and a paring edge C. So far these parts are like similar parts in other devices of this kind and need no further description. The other end of 25 the tubular handle A extends laterally into a plate D having its side edges bent up into circular form in the nature of beads as shown at E in Fig. 4. The outer ends of these beads are cut away as shown at F in 30 Fig. 2, so that the extreme edge G furnishes an uninterrupted chopping or scraping edge. The central part of the plate D beyond the end of the handle A is cut out as shown at H in Fig. 1 and the edge J is 35 bent inward at an incline and sharpened as shown in Fig. 3. The edges G and J are opposite edges of that part of the plate D which is beyond the opening H.

The gage plate K has its sides bent to 40 enter the channels or guides formed by the beads E. In the beaded portion the plate K touches the plate D only at the points K¹ and K² as shown in Fig. 4. Between these points the plates D and K are springs which 45 furnish frictional contact at the points K¹ and K² for holding the gage plate at any desired adjustment from the cutting edge J. A turned up lip M on the gage plate K not only serves as a handle for adjusting it but 50 also as a bridge for preventing the plate from buckling under the spring pressure at

the sides of D and K. The slicing edge J is substantially level with the outer face of the gage plate K and normally prevents the gage plate from being removed from its 55 guides E. A slight pressure, however, on opposite sides of K and J will cause them to spring sufficiently to permit the removal of the gage plate for cleaning.

From the foregoing description it will be 60 seen that this device furnishes a coring point B, a paring knife C, a chopping and scraping edge G, a slicing edge J, and an adjustable gage K for the slicing. Also, that the entire device is made of no more 65 than two pieces of sheet metal with no wires, clips or screws for holding these parts.

What I claim is—

1. In a two-piece device of the character described, a handle and a knife furnishing 70 part having guides formed on the edges thereof, and an adjustable and freely removable gage held in the guides by spring produced frictional contact between the gage and the guides one of said parts being 75 a spring member serving to produce such friction.

2. In a device of the character described, a slicing knife having guides formed at the sides thereof by bending a portion of the 80 metal from which the knife is formed, and an adjustable gage held in said guides by spring compression upon the gage, said gage being a spring member and having a portion bent up to serve as a handle by which it 85 may be manually adjusted and also to serve as a bridge or brace to prevent the gage from buckling under the compression by which it is held.

3. In a device of the character described, 90 a slicing knife having guides formed at the sides thereof by bending a portion of the metal from which the knife is formed, and a gage adjustably held in said guides by frictional contact between the two, said 95 guides being open at the end to permit the free removal of said gage.

4. In a two-piece device of the character described, a handle and a knife furnishing part having opposite edges of the knife part 100 bent to form slotted tubes parallel with the handle, and an adjustable gage having its

opposite edges bent to fit into and engage the inner walls of the tubes, the gage also engaging the knife body at points exterior to the tube whereby the extension of the 5 gage and the knife body beyond the last named engaging points are deflected to form a spring action between the two parts.

Signed at Chicago, Illinois this 15th day of March 1913.

EDWARD B. CASTELLO.
